Patented Jan. 23, 1923.

UNITED STATES PATENT OFFICE.

AXEL CARL VICTOR MALM, OF LANSDOWNE, PENNSYLVANIA, ASSIGNOR TO E. W. BLISS COMPANY, OF BROOKLYN, NEW YORK, A CORPORATION OF WEST VIRGINIA.

PLATEN FOR VULCANIZING PRESSES.

Application filed October 22, 1921. Serial No. 509,690.

To all whom it may concern:

Be it known that I, AXEL C. V. MALM, a citizen of the United States of America, residing in Lansdowne, in the county of Delaware and State of Pennsylvania, have invented certain new and useful Improvements in Platens for Vulcanizing Presses, of which the following is a specification.

This invention relates to platens for platens, and aims to provide improvements therein.

The invention provides a platen of reduced weight and cost, of increased efficiency, and capable of being readily manufactured. 15 The reduced weight renders the platens more easily handled, and the reduced mass enables the platen to be more quickly heated (and cooled), thus hastening such processes as the vulcanization of rubber articles.

20 An embodiment of the invention is illustrated in the accompanying drawing, in which—

Figure 1 is a top plan view of said embodiment;

Fig. 2 is a sectional view on the line 2—2, Fig. 1, and

Fig. 3 is an enlarged detail view (in section) on line 3—3, Fig. 1.

Referring to said drawing, numerals 10 and 11 designate the top and bottom of the platen, 13 the side or sides, and 15 a hollow chamber or space within the platen for receiving a heating or a cooling fluid.

The top and bottom of the platen are 35 formed of plates 17, 18, of pressed metal, as, for example, rolled metal plates or sheets. Such metal is not pervious to gas or vapor under considerable pressures, when of relative thinness. Cast metal would be practically invariably pervious to gas or steam at corresponding thinnesses at which rolled metal would be impervious. Plates of one-half inch thickness give satisfactory results when made into platens subjected to steam pressures of 200 pounds and upward per square inch.

The plates 17, 18, are preferably flat pieces cut from a flat sheet of metal.

The sides 13 of the platen are formed of 50 a metal ring or rings 19, which may be formed as a flange on the plates 17, 18, or preferably as a ring separate from the plates. The ring may be continuous, but is preferably

composed of strips of metal 20 corresponding in number to the number of sides of the 55 platen.

The two plates 17, 18, are joined together, with the ring 19 interposed, by suitable means, as rivets or ties 23, preferably at the margins of the platen and passing through 60 the ring 19. The joints between the two meeting surfaces of the plates 17, 18, and ring, are sealed in suitable manner, preferably by welding, as indicated at 25. Where the plates 17, 18 and ring 19 are separate, 65 the edges of one or the other, conveniently the plates 17, 18, are made so as to project slightly over the outer edge of the other, as indicated at 27, thus forming a pocket for the lodgment of the weld metal.

Ears 29 for stringer rods on a press, may be formed on the plate, and these are conveniently formed as projecting ends of one or more of the separate strips 20, forming 70 the ring 19, as illustrated.

Means are preferably provided for preventing deflection of the top and bottom faces of the platen. This means preferably comprises a strip or strips 30 in the chamber or space 15 between the plates 17, 18, of a 80 thickness corresponding to that of the ring 19, and which act to prevent indentation of the top and bottom under external pressure, and tie pieces or rivets 23 at the middle of the plates, preferably passing 85 through the strips 30, and which act to prevent bulging of the top and bottom of the plates under internal pressure.

Suitable ducts 32, 33, may be provided for the inlet, or inlet and outgo of the heating or 90 cooling medium used.

After the parts have been put together, the top and bottom of the platen are preferably finished to give a true surface.

The inventive ideas herein set forth may 95 receive other mechanical expressions than as herein specifically illustrated and described.

What I claim is:

1. A press platen having a hollow interior for a heating or cooling medium, comprising two substantially flat plates, and means for spacing said plates apart to form an inner chamber and for forming the marginal walls of said inner chamber, said spacing means being constituted by a metal ring 100 around the marginal portion of the platen, 105

said metal ring being in the form of a separate part.

2. A press platen having a hollow interior for a heating or cooling medium, comprising two substantially flat plates, and means for spacing said plates apart to form an inner chamber and for forming the marginal walls of said inner chamber, said spacing means being constituted by a metal ring

10 around the marginal portion of the platen, said ring and plates, projecting one slightly beyond the other, whereby a pocket is formed for welding metal.

3. A press platen having a hollow interior 15 for a heating or cooling medium, comprising two substantially flat plates, and means for spacing said plates apart to form an inner chamber and for forming the marginal walls of said inner chamber, said spacing

20 means being constituted by a metal ring around the marginal portion of the platen, said metal ring being in the form of a separate part, said ring and plates projecting one slightly beyond the other, whereby a 25 pocket is formed for welding metal.

4. A press platen having a hollow interior for a heating or cooling medium, comprising two substantially flat plates, and means for spacing said plates apart to form an inner chamber and for forming the marginal walls of said inner chamber, said plates being formed of pressed metal.

5. A press platen having a hollow interior for a heating or cooling medium, comprising 35 two substantially flat plates, and means for spacing said plates apart to form an inner chamber and for forming the marginal walls of said inner chamber, said plates being formed of pressed metal and being relatively thin, a representative thickness being one-half inch.

6. A press platen having a hollow interior for a heating or cooling medium, comprising two substantially flat plates, and means for 45 spacing said plates apart to form an inner chamber and for forming the marginal walls of said inner chamber, said means comprising spacing pieces in the space between said plates, and ties.

50 7. A press platen having a hollow interior for a heating or cooling medium, comprising two substantially flat plates, means for spacing said plates apart to form an inner chamber and for forming the marginal walls of 55 said inner chamber, and means for sealing

the joint at the meeting surfaces of any two parts of the device.

8. A press platen having a hollow interior for a heating or cooling medium, comprising two substantially flat plates, means for spacing said plates apart to form an inner chamber and for forming the marginal walls of said inner chamber, and means for sealing the joint at the meeting surfaces of any two parts of the device, said means being a weld 60 65 between the parts at the joint.

9. A press platen having a hollow interior for a heating or cooling medium, comprising two substantially flat metal plates, and a metal strip interposed between said plates 70 for spacing said plates apart to form an inner chamber and for forming the marginal walls of said inner chamber.

10. A press platen having a hollow interior for a heating or cooling medium, comprising 75 two substantially flat pressed metal plates, and a metal strip interposed between said plates for spacing said plates apart to form an inner chamber and for forming the marginal walls of said inner chamber.

11. A press platen having a hollow interior for a heating or cooling medium, comprising two substantially flat pressed metal plates, a metal strip interposed between said plates for spacing said plates apart to form an inner chamber and for forming the marginal walls of said inner chamber, and a weld sealing 80 85 the joint between any two meeting surfaces of said plates and strip.

12. A press platen having a hollow interior 90 for a heating or cooling medium, comprising two substantially flat pressed metal plates, a metal strip interposed between said plates for spacing said plates apart to form an inner chamber and for forming the marginal 95 walls of said inner chamber, and spacing pieces in the middle portion of said inner chamber against which said plates are to be fastened to prevent deflection under pressure.

13. A press platen, having a hollow interior for a heating or cooling medium, having two plates of pressed metal forming its top and bottom, and a ring interposed between said plates, the joints between meeting faces of said parts being welded.

In witness whereof, I have hereunto signed my name.

AXEL CARL VICTOR MALM.
